FIG. 1 is a front perspective view of a car seat cover, showing the new design in a fitted configuration;

FIG. 2 is a rear perspective view thereof, illustrated in a flat configuration with a pocket thereof open;

FIG. 3 is a top plan view of FIG. 2;

FIG. 4 is a bottom plan view of FIG. 2;

FIG. 5 is a front elevational view of FIG. 2;

FIG. 6 is a rear elevational view of FIG. 2;

FIG. 7 is a left-side elevational view of FIG. 2;

FIG. 8 is a right-side elevational view of FIG. 2.

FIG. 9 is a top plan view of FIG. 2 except with the pocket closed;

FIG. 10 is a bottom plan view of FIG. 9;

FIG. 11 is a left-side elevational view of FIG. 9; and,

FIG. 12 is a right-side elevational view of FIG. 9.

The broken lines showing a car seat in FIG. 1 are included for the purpose of illustrating the invention in use, and form no part of the claimed design. The remaining broken lines in the figures represent stitching and are part of the claimed design. It is understood that the front and rear elevational views of FIG. 9 are identical to FIGS. 5 and 6 respectively.
